Application March 10, 1950, Serial No. 8,475

Term of patent 3½ years

(Cl. D34—4)

To all whom it may concern:

Be it known that we, Walter B. and Howard C. Bartner, citizens of the United States of America and both residents of the city of Toms River, in the county of Ocean and State of New Jersey, have invented a new, original, and ornamental Design for a Puppet, of which the following is a specification, reference being had to the accompanying drawing, forming a part thereof.

Fig. 1 is a front view of a puppet, showing our new design;

Fig. 2 is a rear view thereof; and

Fig. 3 is a side view thereof.

We claim:

The ornamental design for a puppet, substantially as shown.

WALTER B. BARTNER.
HOWARD C. BARTNER.
